(57) **CLAIM**

The ornamental design for a nut shaped bottle opener, as shown and described.

DESCRIPTION

FIG. 1 is a plan view of the bottom side of my new design for a nut shaped bottle opener with an attachment ring shown in dotted lines which is for illustrative purposes only and is not part of the claimed design.

FIG. 2 is a plan view of the top side of FIG. 1.

FIG. 3 is side elevation view of the left side of FIG. 1.

FIG. 4 is a side elevation view of the right side of FIG. 1. FIG. 5 is a front side elevation view of FIG. 1 without the attachment ring shown.

FIG. 6 is a rear side elevation view of FIG. 1 without the attachment ring shown.

FIG. 7 is a bottom perspective view of FIG. 1.

FIG. 8 is a plan view of the bottom side of an alternate embodiment with magnets of my new design for a nut shaped bottle opener with an attachment ring shown in dotted lines which is for illustrative purposes only and is not part of the claimed design.

FIG. 9 is a plan view of the top side of FIG. 8.

FIG. 10 is side elevation view of the left side of FIG. 8.

FIG. 11 is a side elevation view of the right side of FIG. 8. FIG. 12 is a front side elevation view of FIG. 8 without the attachment ring shown.

FIG. 13 is a rear side elevation view of FIG. 8 without the attachment ring shown; and,

FIG. 14 is a bottom perspective view of FIG. 8.
